UNITED STATES PATENT OFFICE.

LYDIA EMELINE PATTEE, OF SMITH CENTRE, KANSAS.

MILK-CATCHER FOR NURSING-WOMEN.

SPECIFICATION forming part of Letters Patent No. 296,609, dated April 8, 1884.

Application filed July 20, 1883. (No model.)

To all whom it may concern.

Be it known that I, LYDIA EMELINE PATTEE, a citizen of the United States, residing at Smith Centre, in the county of Smith and State of 5 Kansas, have invented certain new and useful Improvements in Milk-Catchers for Nursing-Women; and I do hereby declare the following to be a full, clear, and exact description of the invention, such as will enable others skilled 10 in the art to which it appertains to make and use the same.

This invention relates to improvements in milk-catchers for nursing-women, and has for its objects to prevent the milk from wetting 15 the clothing, and to improve the form. These objects are attained by the apparatus illustrated in the accompanying drawings, forming a part of this specification, in which—

Figure 1 is an elevation taken from the side 20 next the body. Fig. 2 is a front elevation. Fig. 3 is a sectional view. Fig. 4 is a view showing the milk-catchers or protectors adjusted to the person.

The letter A represents the convex side of 25 the protector. B is the concave side. b b' are short straps having button-holes. e e are elastic straps passing over the shoulders, and connected to each other by the strap f. The straps e e are provided with flat buttons, which 30 are buttoned to the short straps b, whereby the breast - protectors are suspended. The shoulder-straps e e are attached to the belt E at the back. e' e' are short straps, having flat buttons, which are buttoned to the short straps 35 b' b'. The lower ends of straps e' e' are at-

tached to the belt E, whereby the breast-protectors are held down and retained in the proper position on the body of the wearer. The belt E is fastened by a button in front, or in any other convenient manner. a is an orifice to receive the nipple, and is placed on the concave surface of the protector.

I prefer to make the protectors of white rubber or gutta - percha, the same material of which are made the bulbs of breast-pumps and 45 the nipples of nursery bottles. As this is flexible, it will not bruise the breast, and has this advantage over a breast - protector made of any rigid substance, such as glass; and the manner of fastening it to the body of the wearer 50 enables it to be kept in place without any hard pressure on the breast.

The letter C indicates a small orifice for emptying the contents of the breast-protector.

Having described my invention, what I desire to claim, and secure by Letters Patent, is—

In a milk-catcher for nursing-women, the protector A, having concave side B, orifice a, and orifice C, made of flexible material, and provided with short button-hole straps b b', in 60 combination with elastic straps e e, having cross-strap f, and straps e' e', attached to the belt E, as shown and described, and for the purposes set forth.

In testimony whereof I affix my signature in 65 presence of two witnesses.

LYDIA EMELINE PATTEE.
